UNITED STATES PATENT OFFICE

171,008

BOTTLE HOLDER

James A. Peterson, Yorkville, Ill.

Application July 9, 1953, Serial No. 25,860

Term of patent 14 years

(Cl. D58—26)

To all whom it may concern:

Be it known that I, James A. Peterson, a citizen of the United States, residing at Yorkville, county of Kendall, State of Illinois, have invented a new, original, and ornamental Design for a Bottle Holder, of which the following is a specification, reference being had to the accompanying drawing, forming a part hereof.

In the drawing:

Fig. 1 is a side elevation of a bottle holder embodying my design.

Fig. 2 is a front elevation looking toward the left-hand side of Fig. 1.

Fig. 3 is a top plan view of Fig. 1.

I claim:

The ornamental design for a bottle holder, as shown.

JAMES A. PETERSON.
